UNITED STATES PATENT OFFICE.

ARTHUR J. BRIGGS, OF SYRACUSE, NEW YORK, ASSIGNOR TO NATIONAL CARBON COMPANY, INC., A CORPORATION OF NEW YORK.

EXTRUDED DEPOLARIZING BOBBIN.

Application filed March 31, 1922. Serial No. 548,420.

This invention relates to depolarizing bobbins for electric cells and to processes and apparatus for preparing the same. The object of the invention is to improve the 5 quality of such articles and to provide new forms thereof, as well as to decrease the costs and time of manufacture.

The invention includes bobbins having a new type of supporting covering, and improved forms of bobbin especially suitable 10 for deferred action cells of the water-activated type, and it contemplates the application of extrusion apparatus and processes to the production of such bobbins, all as hereinafter more particularly described, and as 15 claimed.

It has heretofore been proposed to prepare tubular mix bobbins by extrusion, to force a cylindrical carbon electrode into the 20 perforation through each bobbin while the composition retains its plasticity, and to wrap the bobbins in a suitable fabric subsequent to the insertion of the electrode. According to the present invention, the 25 wrapping is effected by mechanical means as the composition is extruded. The carbon electrodes are then inserted in the wrapped bobbins. In following the prior procedure, a large percentage of bobbins is 30 broken, as the unsupported depolarizing material is easily disrupted by the outward pressure exerted by the electrode forced into the central opening of the bobbin. In the improved method, on the contrary, the 35 wrapping engaging its peripheral surface sustains or reinforces the material, permitting the insertion of a carbon electrode of sufficient size to insure adequate electrical connection between depolarizer and electrode, without danger of damaging or 40 destroying the bobbin. In addition, the process of manufacture is greatly expedited by continuously wrapping the extruded material, instead of separately wrapping each 45 bobbin.

In the accompanying drawings, illustrating a preferred embodiment of the invention,

Fig. 1 is a longitudinal section through an extrusion and wrapping machine,

Fig. 2 is a longitudinal section through a modified extrusion die,

Fig. 3 is a transverse section on line 3—3 of Fig. 2,

Fig. 4 is a perspective view of a wrapped 55 body of mix, and

Figs. 5 and 6 show mix bobbins provided with a plurality of vertical perforations, the former figure in elevation and the latter in transverse section. 60

Referring to Fig. 1 of the drawings, plastic depolarizing material 1 is forced forwardly through the funnel shaped member 2, preferably by substantially constant pressure derived from any suitable source. The 65 funnel 2 terminates in a tubular extension 3 which operates as a die in forming an extruded body of the chosen diameter. When it is desired to provide the body with a cylindrical perforation, a core for the die 70 consisting of a rod 4 of suitable cross-section is mounted in a spider 5 rigidly attached to the funnel wall. The rod 4 extends outwardly well beyond the tubular extension 3 and is preferably co-axial with the extension. The extended portion of the rod 75 serves to support the extruded plastic during the wrapping operation.

The means for applying a protective wrapping to the extruded body comprises a reel 80 carrier 6, journaled on extension 3 and held thereon by any suitable means. The carrier is adapted to be rotated about the longitudinal axis of the extruded body by means of a pulley 7, driven by belt 8. An inclined reel 9 is mounted upon an arm 10, integral 85 with carrier 6. The arm 10 carries a bracket 11 to which is secured a guide rod 12 extending in close parallel relation to the extruded body. The fabric or other material 90 13 carried by the reel passes between the guide rod and the extruded body.

Rotation of the carrier 6 causes the fabric carried by the reel to be continuously drawn off and wrapped in an overlapping helix about the extruded mix. Guide rod 12 95 presses the fabric toward the mix to insure tight wrapping. If desired, the guide rod may be made adjustable so as to permit regulation of the tension at which the fabric is supplied. It may be stated that the term "fabric," as used herein respecting the relatively wide continuous sheet or band 13, is to be considered generic to all of the bibulous materials which are suitable for 100 wrapping mix bobbins.

The preferred means for securing the fabric about the mix comprises a container

14 arranged to discharge a regulated stream of paste or other adhesive material. A wiper 15, rotated by a pulley 16, engages the wrapping and uniformly distributes upon 5 it the material supplied from container 14. The pulley 16 is preferably integral with an extension 17 keyed to a cylinder 18. Surrounding the major portion of the cylinder 18 is a heating chamber 19, in which 10 the adhesive is hardened. Gas flames 20 or any other suitable source of heat may be supplied in the heating chamber. In the arrangement shown, belt 21 rotates the cylinder 18, so as to present all parts of its surface 15 to the source of heat.

Instead of pasting the fabric, it may be secured by tying or the like. In some cases, also, the fabric may be omitted, and paste or other suitable material adapted to harden 20 upon the bobbin surface may be applied directly thereto.

Any desired means for severing the elongated tubular body may be adopted. An eccentrically mounted cutting disc 22 has been 25 illustrated by way of example. The severed portions may be delivered to packing devices or otherwise disposed of. If the product is wrapped depolarizing mix, carbon rods may be inserted by hand or the tubular sections 30 may be fed into any suitable type of machine for automatic insertion of the rods. A wrapped bobbin so prepared is illustrated in Fig. 4. It will be noted that the ends of the bobbin are not covered. For many purposes 35 the bobbin may be left in this condition, but discs of paper or the like may of course be placed over the ends, if desired. An advantage of the improved bobbin is the elimination of the objectionable bunching of fabric about the projecting end of the carbon rod, common to prior wrapped bobbins.

In the modified form of the invention 45 illustrated in Figs. 2 and 3, a plurality of slender rods 23 are seated in the spider 5 and pass through extension 3 in parallel relation to the core rod 4. This arrangement is especially designed for the production of mix bobbins for use in deferred action cells of the water activated type. The numerous 50 perforations formed in the mix, by forcing it about rods 23, permit rapid absorption and even distribution of the activating liquid. A bobbin of this type, with cylindrical vertical openings 24, is shown in Fig. 5. Perforations 24', of a different shape, are illustrated in Fig. 6. Obviously the size, shape 55 and location of the perforations may be greatly varied. They may be very conveniently made during the extrusion operation, as described, but may also be formed in other ways. For example ordinary tamped bobbins, or the extruded bobbins described herein, may be punched or bored to give the desired number of openings, and these need not 60 extend entirely through the bobbin.

The cylindrical conformation of the bobbin and its axial perforation is shown by way of example only, as the shape of the extruded body may be varied according to its intended use. It is preferred to extrude the 70 plastic material continuously, but an intermittent feed may be used, the wrapping and severing devices being synchronized with the movement of the extruded body. Various other departures from the specific form illustrated herein fall within the scope of the appended claims. 75

I claim:

1. A depolarizer for dry cells having a covering engaging its peripheral surface, 80 said covering comprising a single continuous helically extending sheet of bibulous material.

2. A depolarizer according to claim 1, wherein portions of said sheet overlap one another. 85

3. A substantially cylindrical bobbin of depolarizing material having a protective and reinforcing covering engaging and united to only the cylindrical surface of said bobbin, leaving the ends of the latter un- 90 covered.

4. A depolarizer for dry cells having a protective and reinforcing covering on its peripheral surface, said covering comprising a helically extending sheet of bibulous material and a coating of hardened adhesive composition. 95

5. As a new article of manufacture, an extruded depolarizer body for dry cells, and a covering on the peripheral surface of said 100 body, said covering comprising a helically extending sheet of bibulous material engaging said body.

6. As a new article of manufacture, an extruded depolarizer body and a covering on 105 the peripheral surface of said body, said covering comprising a hardened adhesive composition.

7. As a new article of manufacture, an extruded body of depolarizing material having 110 a hole extending therethrough, and a protective and reinforcing covering on the peripheral surface of said body, said covering comprising a hardened adhesive composition.

8. As a new article of manufacture, an extruded tubular depolarizer body having a protective and reinforcing covering on its peripheral surface, such covering comprising a helically extending sheet of bibulous material and a coating of hardened adhesive 120 composition. 115

9. An elongated body of depolarizing material having a reinforcing and protecting covering engaging the peripheral surface of said body, said body being of such length 125 that it may be divided into a plurality of depolarizing units, each peripherally reinforced and protected by a covering.

In testimony whereof, I affix my signature.
ARTHUR J. BRIGGS.
